Patented Feb. 16, 1915

2 SHEETS - SHEET 1

UNITED STATES PATENT OFFICE.

BARNETTE T. STEINER, OF CANTON, OHIO, ASSIGNOR TO THE GILLIAM MANUFACTURING COMPANY, OF CANTON, OHIO, A CORPORATION OF OHIO.

BOW-CLAMPING DEVICE.

1,128,541.

Specification of Letters Patent. Patented Feb. 16, 1915.

Application filed March 16, 1910, Serial No. 549,755. Renewed April 20, 1914. Serial No. 833,181.

To all whom it may concern:

Be it known that I, BARNETTE T. STEINER, a citizen of the United States, residing at Canton, in the county of Stark and State of Ohio, have invented certain new and useful Improvements in and Relating to Bow-Clamping Devices, of which the following is a specification.

This invention relates to a bow rest and clamping device for vehicles adapted to facilitate the positive clamping of the bows of a collapsible vehicle top in closed position, and the releasing of the bows when the top is to be opened.

For the purposes of illustration I have, in the accompanying drawings, shown and herein described, one form of bow rest embodying my invention.

Figure 1 is a side elevation of a portion of a vehicle, showing a bow rest embodying my invention, in use. Fig. 2 is an elevation of the bow rest, parts being shown in section. Fig. 3 is an elevation looking toward the right of Fig. 2. Fig. 4 is a plan view of Fig. 2. Fig. 5 is an elevation of a bow rest and clamp, partly in section, to facilitate the illustration taken on the line 5—5 of Fig. 3. Fig. 6 is a longitudinal sectional view of the device taken on the line 6—6 of Fig. 2. Figs. 7 and 8 are transverse sectional views on the lines 7—7 and 8—8, respectively, of Fig. 6. Fig. 9 is a transverse section on the line 9—9 of Fig. 5.

In the drawings, 1 indicates a vehicle having a collapsible top 1^a supported in any usual or preferred manner by bows 1^b.

2 indicates a bracket or arm, having an opening 2^a, preferably of conical shape, at or near its free end. The bracket or arm 2 is secured to the body of the vehicle in any preferred manner.

3 indicates as an entirety a support preferably depending from the bracket 2. The upper end 3^a of the support is reduced, and extends through the opening 2^a of the bracket 2. The reduced end is preferably provided with screw threads 3^b to take a nut 3^c.

3^b indicates an expanding conically shaped collar surrounding the reduced portion 3^a of the support 3 and adapted to closely fit the opening 2^a. By screwing down the nut 3^c upon the reduced end 3^a,

the collar 3^b will be contracted into snug engagement with the reduced end 3^a and result in rigidly securing the support 3 to the bracket 2. The lower end of the support 3 is provided with a laterally extending arm 3^d.

3^e indicates a rest, relative to which a clamp device, indicated as an entirety at 5, moves to clamp and release the bows 1^b of the top 1^a. This rest preferably comprises a semi-circular plate provided with a sleeve or collar 3^e fitting over the arm 3^d. A suitable set screw is provided for fixing the rest at any position desired on the arm 3^d. The plate 3^e operates as a rest to receive and support the bows 1^b when the top is closed, as shown in Fig. 1.

The support 3 preferably comprises a main supporting member 3^x and a supplemental or auxiliary support 4. As shown at 3^f, the main support 3^x is extended laterally to form a base. The base 3^f may be formed with an opening 3^g to receive the supplemental support 4.

4^a indicates a pin or key extending through suitable apertures formed in the support 3^x and spindle 4 for rigidly securing the latter in the recess 3^g.

4^b indicates a series of ratchet teeth provided along one side of the supplemental support 4.

The clamp device 5 is slidably mounted upon the spindle 4 and also rotatable thereon in order that the clamp device may be swung into the position indicated by the dotted lines in Fig. 4 to facilitate the closing of the bows. The clamp device 5 preferably comprises a slidable member 5^c such as a sleeve, carrying a laterally extending plate-supporting arm 5^d and a lock-and-release or interlocking mechanism 6 for locking and releasing the clamp device.

5^e indicates a plate, preferably of semi-circular shape, adjustably mounted upon the arm 5^d. The plate 5^e is preferably similar in construction to the plate or rest 3^e and may be adjustably fixed to the arm 5^d by a set screw 5^f. This plate aligns with the plate or rest 3^e and engages the uppermost bow of the series of bows to clamp the top in closed position.

The lock-and-release mechanism is preferably inclosed by a casing, such as indicated

- at 6^a. This casing 6^a is detachably secured to the sleeve 5^c by suitable devices, such as screws or bolts, 6^a, 6^b.
- 6^b indicates an opening formed in the casing 6^a and arranged to align with an opening 5^c formed in the adjacent side of the slideable member 5^c.
- 6^c, 6^e, indicate a pair of supports arranged within the casing 6^a.
- 10 6^d indicates a pin or shaft supported by the supports or plates 6^c.
- 6^e indicates a pawl pivotally mounted upon the pin 6^a. The pawl 6^e preferably extends upwardly and through the aligned openings 6^b, 5^c in the casing 6^a and sleeve 5^c, respectively, so that its free end engages with the ratchet teeth 4^b of the supporting member 4.
- 15 6^f, 6^f, indicates a pair of arms fixed to the pawl 6^e and extending rearwardly therefrom.
- 6^g indicates a thrust rod extending between the arms 6^f. The thrust rod is provided with screw threads adapted to receive 25 nuts 6^h which are arranged upon and engage with the opposite sides of the arms 6^f, whereby the operation of the pawl 6^e may be controlled by the rectilinear movement of the thrust rod 6^g.
- 30 6ⁱ indicates a collar or spacing device interposed between one of the nuts 6^h and an abutment 6^j to limit the movement of the pawl 6^e in one direction. The abutment 6^j is formed with an opening 6^l through which 35 the thrust rod 6^g extends. It will be understood, that by adjusting the nuts 6^h, 6ⁱ, the pawl 6^e may be regulated or adjusted to operate in a positive and accurate manner.
- 35 The upper end of the thrust rod 6^g extends through the casing and is provided at its free end with a cap or push button 6^l. The casing 6^a is preferably provided with a tubular projection 6^k over which the cap or button 6^l slidably fits. This construction of cap and tubular projection operates as a guiding device for the upper end of the thrust rod, it being guided near its opposite end by the walls of the opening 6^l formed in the abutment 6^j.
- 40 6^m indicates a spring, preferably coiled around the rod 6^g. One end of the spring 6^m engages the abutment 6^j, and its opposite end engages with the cap 6^l. The spring 6^m operates to normally thrust the rod upwardly and to throw the pawl 6^e outwardly and into engagement with the ratchet teeth 4^b provided on the spindle 4.
- 45 It will be understood that by pressing downward upon the cap or button 6^l, the pawl will be released from the teeth 4^b, whereby the clamp member 5 may be elevated and rotated on the supporting member 4, or it may be entirely removed therefrom.
- 50 65 When the vehicle top is thrown up, the clamp device lies in the position indicated in Figs. 5 and 6, with the lower end of the sleeve 5^c engaging with the base 3^f.
- 7 indicate interlocking devices between the support 3 and clamp device 5, operating 70 to prevent rotation of the clamp device when in its lowermost position. These devices preferably comprise a pin 7^a, carried by one of the parts, and an aperture 7^b formed in the other part and adapted to receive 75 the pin 7^a. In the construction illustrated, the pin 7^a is supported by and extends upwardly from the base 3^f, and fits into the aperture 7^b formed therefor in the clamp device.
- 8 indicates a cushioning and yielding device 80 preferably comprising a coiled spring supported in a recess 4^d in the upper end of the supplemental support 4.
- 4^e indicates a screw or other device for 85 securing the cushioning means in position.
- The cushioning and yielding device 8 extends beyond the upper end of the supplemental support 4 and engages with the end wall of the sleeve 5^c to prevent the latter 90 from falling into its lowermost position with a jar, which might result in fracturing the clamp device 5. It will be understood that the device 8 being yieldable, is placed under compression when the clamp 95 device 5 is operated to clamp the bows 1^b. In this manner it tends to push the clamp member upwardly, thus coöperating with the spring 6^m to maintain the lock and release mechanism in operative engagement 100 with the ratchet teeth 4^b, and at the same time overcoming any tendency of the parts to rattle.
- In the operation of my clamp device, it will be understood that prior to the closing 105 of the vehicle top, the pawl 6^e is released from the ratchet 4^b by the downward pressure upon the button 6^l, whereupon the clamp device is elevated and rotated on the supplemental support 4 into a position at 110 substantially right angles to its normal position, as indicated in dotted lines in Fig. 4. When the clamp device is in this position, the bows of the vehicle top may be swung downwardly in closed position with 115 the lowermost bow resting upon the plate 3^e, and the other bows of the series of bows superposed above it. The clamp device 5 is then moved back into normal position and pressed downwardly against the 120 uppermost bow. As the clamp device is pressed downwardly in this manner, the pawl 6^e will automatically engage with one of the ratchet teeth 4^b and lock the clamp device in this position, thus securing and 125 holding closed all of the bows. It will be understood that in operating the clamp device to permit the closing of the bows, it may be entirely removed from the support 4, and after the bows have been closed the 130

clamp device may be replaced upon the support and the bows clamped, as above described.

To those skilled in the art of making devices of the class described, many alterations in construction and widely differing embodiments and applications of my invention will suggest themselves, without departing from the spirit and scope thereof.

10 My disclosures and the description herein are purely illustrative, and are not intended to be in any sense limiting.

What I claim is—

1. A bow supporting and clamping mechanism comprising a base, including a rest on which the lowermost bow of the vehicle top is supported, a support mounted thereon, a clamping member arranged to slidably fit over said support, the said clamping member including a plate arranged to engage the uppermost bow of the top, interlocking mechanism between said clamp member and said support, and a casing enclosing said interlocking mechanism, removably connected to said clamp member.

2. A bow supporting and clamping mechanism comprising a rest or base member, a spindle mounted thereon and provided with a series of ratchet teeth, a clamp member slidably fitting said spindle, a casing detachably connected to said clamp member, a pawl mounted within said casing, the casing and clamp member being provided with aligned openings to permit the pawl to engage the teeth of said spindle, and a spring operated rod slidably mounted within the casing for operating said pawl, the free end of the rod extending through the casing to permit its operation.

3. A bow supporting and clamping mechanism comprising a rest or base member, a spindle mounted thereon and provided with a series of ratchet teeth, a clamp member slidably fitting said spindle, a casing detachably connected to said clamp member, a pawl mounted within said casing, the casing and clamp member being provided with aligned openings to permit the pawl to engage the teeth on said spindle, a spring operated rod slidably mounted within the casing for operating said pawl, the free end of the rod extending through the casing to permit its operation, and means carried by the free end of the rod for guiding and supporting said end.

4. In a bow rest and clamp for a vehicle top, the combination of supporting means provided with a rest with which the bows of a vehicle top engage when closed, and an auxiliary support, a clamp device slidably mounted on the auxiliary support and provided with a bow-engaging plate coöperating with the rest when the bows are clamped, means for securing the clamp device in clamping position on the auxiliary

support, and cushioning means for the clamp device, the cushioning means coöperating with the clamp device securing means for maintaining the said device in locked position.

5. In a bow rest and clamp for a vehicle top, the combination of supporting means provided with a rest with which the bows of a vehicle top engage when closed, and an auxiliary support, a clamp device slidably mounted on the auxiliary support and provided with a bow-engaging plate coöperating with the rest when the bows are clamped, means for securing the clamp device in clamping position on the auxiliary support, interlocking devices between the auxiliary support and the clamp device for positioning the latter when the bows of the vehicle top are thrown up or folded down, and a yieldable device interposed between the auxiliary support and the clamp device normally maintaining the interlocking devices in operative position and permitting their operation to release the said clamp device.

6. In a device of the character described, the combination of supporting means including a rest on which the bows of a vehicle top are supported when collapsed, a clamp member mounted on said supporting means and arranged to be adjusted thereon up and down and angularly, the said member being provided with a plate coöperating with the rest to clamp the bows therebetween, a coil spring surrounding the axis about which the said clamp member swings when moved angularly and arranged to be compressed when said clamp member is moved downwardly and clamped, and spring-controlled means arranged below the coil spring for holding the clamp member in operative position.

7. In a device of the character described, the combination of supporting means arranged at one side of a vehicle and provided with a rest on which the bows of the vehicle top are supported, a clamp member mounted on said supporting means and arranged to be adjusted vertically and angularly relative thereto, the said member being provided with a plate arranged to engage the uppermost bow of the top and co-operate with the rest to clamp the bows therebetween, a coil spring interposed between the supporting means and the clamp member and surrounding the axis about which the clamp member swings when adjusted angularly and arranged to be compressed when said clamp member is moved downwardly, and spring-controlled means for holding said clamp plate and supporting means in adjusted position relative to each other and against the tendency of said spring to separate them.

8. In a device of the character described,

70

75

80

- the combination of a pair of members having bow engaging plates arranged to support and clamp the bows between them, one of said members being stationary and pivoted with ratchet teeth, and the other of said members being movable relative to said first-mentioned member and provided with a pivoted pawl arranged to engage the ratchet teeth of said first-mentioned member, spring-controlled means connected with said pawl and operating to swing its teeth-engaging end laterally and into engagement with said ratchet teeth, and a spring interposed between said members normally operating to move said movable member vertically, and coöperating with said spring-controlled means for the pawl to hold the latter in engagement with said ratchet teeth.
9. In a device of the character described, the combination of a supporting means including a rest on which the bows of a vehicle top are supported when collapsed, a clamp member mounted on said supporting means and arranged to be adjusted thereon up and down and angularly, the said member being provided with a plate coöperat-
- ing with the rest to clamp the bows therebetween, a coil spring surrounding the axis about which the clamp member swings when moved angularly and arranged to be compressed when said member is moved downwardly and clamped, and a spring-controlled means for holding the clamp member in operative position.
10. In a bow rest and clamp for a vehicle top, the combination of a support having a rest and an upright member, a clamp device slidably mounted on said upright member and having a bow engaging member adapted to coöperate with the rest for holding the bows when folded, means for securing the clamp device in operative position on the upright member, and cushioning means for the clamp device, the said cushioning means coöperating with the clamp device securing means for maintaining the said device in locked position.
